ATTORNEY

UNITED STATES PATENT OFFICE.

SMITH H. ELLIOTT, OF WALTHILL, NEBRASKA.

TANK-HEATER.

1,261,799.

Specification of Letters Patent. Patented Apr. 9, 1918.

Application filed June 29, 1917. Serial No. 177,733.

To all whom it may concern:

Be it known that I, SMITH H. ELLIOTT, a citizen of the United States, and a resident of Walthill, in the county of Thurston and 5 State of Nebraska, have invented certain new and useful Improvements in Tank-Heaters, of which the following is a specification.

The present invention relates to tank 10 heaters.

The invention aims to provide an improved heater for stock-waterers, or other water containers.

A further object of the invention is the 15 production of a simplified and inexpensive oil heater embodying certain novel features adapting it to be readily installed within and removed from a water tank.

With these and other objects in view, the 20 invention, consisting in the construction, combination and novel arrangement of parts, will be clearly understood from the following description, reference being had to the accompanying drawings, which form a 25 part of this application, and in which like characters of reference indicate corresponding parts throughout the several view, of which,—

Figure 1 is a vertical section of an advantageous embodiment of the invention installed in a water tank; Fig. 2 is a side elevation of the burner; Fig. 3 is a plan of the same; Fig. 4 is a vertical section of the jet; and Fig. 5 is a plan of the circulating coil.

Referring, now, to the illustrations, 35 represents a stock watering tank, on the bottom of which is set the heater comprising a casing, 7, having a bottom, 8, and a draft flue, 9, at its upper end which extends above 40 the water line. The casing communicates at its side with a large air inlet flue, 10, extending obliquely a distance above the water line. Within the flue 10, and secured to the bottom thereof, is a pipe, 11, extending 45 above the flue and having its upper end turned downwardly and introduced into a tank, 12, supported by the pipe, and adapted to contain oil to be forced by pressure into the pipe, 11. The pipe is provided with 50 a controlling valve, 13.

The burner consists of a horizontal pipe coil, 14, preferably spiral-shaped and having its outer end portion turned downwardly, as at 15, to receive from the pipe, 11, and support the coil. The inner end por-

tion of the coil is turned downwardly, as at 16, and provided with a cap, 17, threaded thereon and preferably so related thereto that there is a space 24' between the end of the cap and the end of the said portion of the coil. The end of the cap is provided with a central opening, 18, which freely incloses a plug, 24, having a conical head, 25, seated on the end of the cap to cover the opening and support the plug. The plug 60 serves as a jet, having an axial bore, 26, for the emission of the gas.

The conical head, 25, prevents accumulation of carbon, and other by-products of the fuel, at a point where it could obstruct 70 the jet bore, for obviously refuse material will not remain on the head but drop into the space around the head and between the end of the cap and the end of the coil, which space is readily cleaned by forcing the plug 75 upwardly and inserting a suitable instrument into the hole 18, to remove the contents of the cap.

Below the burner is a saucer, 19, having an ear, 20, slidably supported by and reasonably fixed to the pipe portion, 15, by means of a set-screw, 21, whereby the saucer may be adjusted toward and from the jet.

Above the saucer is a pipe-coil, 22, having superposed helices, the end portions of 80 said coil being extended through and secured to the wall of the casing as by nuts, 23, on the opposite sides of the wall.

To light the burner, the saucer is filled with oil from the jet and then lighted to 90 heat the coil, 14, whereby the oil is converted into a gas which ignites at the jet. Obviously the flame from the jet is forced against the saucer which spreads and reflects the flame to heat both the coils, 14, 95 and 22.

It is evident the water is heated by being siphoned through the heated coil, 22.

Having thus described my invention what I claim as new and desire to secure by Letters Patent of the United States is,—

1. A heater including an oil container, a feed pipe to receive therefrom, and a burner including a spiral pipe coil having its outer end extended downwardly and connected 105 with the feed pipe to receive from the feed pipe, the inner end of the coil being extended downwardly and provided with a jet, and a saucer supported by said first portion below the coil, adjustable toward and 110

from the coil, and adapted to receive oil to heat the coil and spread and reflect the flame from the jet.

2. A heater including an oil container, a feed pipe to receive therefrom, and a burner including a spiral pipe coil having its outer end portion extended downwardly and connected with the feed pipe to receive from the feed pipe and support the coil, the inner end 10 of the coil being extended downwardly and provided with a jet, and a saucer supported by said first portion below the coil, and adapted to receive oil to heat the coil and spread and reflect the flame from the jet.
- 15 3. A heater including a pipe coil having a downwardly turned end, a cap thereon having an opening in its end, and a jet including a plug freely inclosed by said opening, and having a passage therethrough 20 and a head on the plug resting on the end of the cap to close the opening, and support the plug.

4. A heater including a pipe coil having

a downwardly directed end, a cap thereon having an opening in its end and a jet including a plug freely inclosed by said opening, having a gas passage therethrough and a conical head on the plug resting on the end of the cap to close the opening and prevent accumulation of refuse on the plug and around its bore.

25 5. A heater including a pipe coil having a downwardly directed end, a cap threaded thereon, and so related thereto as to provide a space between the end of the coil and the end of the cap, the cap having an opening in its end, and a jet including a plug freely inclosed by the opening, having a gas passage and a conical head resting on the end of the cap to close the opening and prevent accumulation of refuse on the plug and around its bore.

35 40 In testimony whereof, I have hereunto set my hand this 25th day of June, 1917.

SMITH H. ELLIOTT.
